SUPPORT DEVICE FOR FISHING LANTERN OR THE LIKE

Eugene C. Andrews, 143 Woodlake Drive,
Gainesville, Ga. 30501

Filed Mar. 12, 1974, Ser. No. 450,304

Term of patent 14 years

Int. Cl. D8—08

U.S. Cl. D8—233

FIG. 1 is a side elevational view of my support device for fishing lantern or the like, the dotted line portions of the figure not forming a part of my design and being merely for the purpose of showing typical environmental structure with which my design may be associated, such as when it is mounted upon the gunwale of a boat and employed for supporting a lantern; and

FIG. 2 is a top plan view of my support device for fishing lantern or the like.

I claim:

The ornamental design for a support device for fishing lantern or the like, as shown and described.
